CLAIM

The ornamental design for a water display system, as shown and described.

DESCRIPTION

FIG. 1 is a perspective view of the display system installed within a wall, the wall depicted in phantom and forming no part of the claimed design. The distribution piping is concealably installed behind the wall.

FIG. 2 is a perspective view of the entire water display system including the distribution piping.

FIG. 3 is a top view of the water display system.

FIG. 4 is a bottom view of the water display system.

FIG. 5 is a rear view of the water display system.

FIG. 6 is a front view of the water display system.

FIG. 7 is a left side view of the water display system; and, FIG. 8 is a right side view of the water display system.
